COMBINED DISPLAY AND DISPENSING STAND

Frank Mellion, Providence, R.I., assignor to Jo-Dee Corp., Warwick, R.I., a corporation of Rhode Island

Filed Apr. 1, 1965, Ser. No. 84,591

Term of patent 14 years

(Cl. D80—9)

FIG. 1 is a side elevational view of a combined display and dispensing stand, showing my new design;

FIG. 2 is another side elevational view taken from a position 60° from that of FIG. 1;

FIG. 3 is a top plan view thereof;

FIG. 4 is a bottom plan view thereof; and

FIG. 5 is a cross sectional view taken along line 5—5 of FIG. 1.

The broken-line representation of packages in FIG. 1 is for purposes of illustration only.

I claim:

The ornamental design for a combined display and dispensing stand, substantially as shown and described.
